CLAIM

The ornamental design for footwear, as shown and described.

DESCRIPTION

FIG. 1 is a top, right perspective view of footwear showing the new design;

FIG. 2 is a bottom, left perspective view thereof;

FIG. 3 is a top, left perspective view thereof;

FIG. 4 is a bottom, right perspective view thereof;

FIG. 5 is a front elevation view of thereof;

FIG. 6 is a rear elevation view of thereof;

FIG. 7 is a left side view thereof;

FIG. 8 is a right side view thereof;

FIG. 9 is a top plan view thereof; and,

FIG. 10 is a bottom plan view thereof.

The dot-dash broken lines show features of the footwear that form no part of the claimed design. The even length broken lines on the footwear upper depict stitching, which forms no part of the claimed design.
